ELECTRONIC CASH REGISTER

Lynton Randolph Knapp, Orange, and Ralph Waldo Province, Westminster, Calif., assignors to MSI Data Corporation, Costa Mesa, Calif.

Filed Feb. 10, 1972, Ser. No. 225,363

Term of patent 14 years

Int. Cl. D18—01; D14—02
U.S. Cl. D52—4 A

FIG. 1

FIG. 1 is a front and left side perspective view of an electronic cash register showing our new design, the right side being identical thereto;

FIG. 2 is a partial top plan view thereof taken from line 2—2 of FIG. 3; and

FIG. 3 is a rear elevational view thereof.

We claim:

The ornamental design for an electronic cash register, as shown and described.
